TO GENERAL ELECTRIC COMPANY, A CORPORATION OF NEW YORK.

INVERSE TIME-LIMIT RELAY.

1,294,305.

Specification of Letters Patent. Patented Feb. 11, 1919.

Application filed September 15, 1914. Serial No. 861,904.

To all whom it may concern:

Be it known that we, LEWIS T. ROBINSON and CLYDE V. HARDY, citizens of the United States, both residing at Schenectady, in the county of Schenectady, State of New York, have invented certain new and useful Improvements in Inverse Time-Limit Relays, of which the following is a specification.

Our invention relates to inverse time limit 10 relays and particularly to inverse time limit overload relays having two movable contact members adapted to control the circuit of the tripping coil of a circuit breaking device.

The object of our invention is broadly 15 to improve the construction of inverse time limit relays, thereby providing a relay of novel and improved construction. A more particular object of our invention is to provide in an inverse time limit relay having 20 two movable contact members an arrangement whereby the minimum time of engagement of the contact members can be simply, conveniently, and accurately adjusted. A further object of our invention is to provide 25 in a relay of the above mentioned type a novel and improved mechanism for actuating one of the movable contact members at a predetermined, definite speed. A still further object of our invention is to provide 30 an inverse time limit relay in which the characteristic relation between time and an electrical characteristic, such as current, may be suitably adjusted by convenient and simple means, and further to provide a relay 35 in which accurate selective action for different overloads and certainty of the correct order of operation of circuit breaking switches under all conditions may be satisfactorily obtained. Other objects of our invention will be evident from the subsequent 40 description of an inverse time limit overload relay embodying the invention.

The features of our invention which we consider patentably novel are definitely indicated in the claims appended hereto. The construction and mode of operation of an inverse time limit relay embodying the invention will be understood from the following description taken in connection with 50 the accompanying drawings, in which;

Figure 1 is a diagrammatic view in perspective of our novel and improved inverse time limit relay operatively connected to an electrical installation, and Figs. 2 and 3 are 55 explanatory diagrams.

The inverse time limit relay of our invention comprises two movable contact members adapted to control the electric circuit of the tripping coil of a circuit breaking device. The two contact members have coincident paths of movement and one contact member is adapted to occupy a position whose distance from the initial position of the other contact member is an inverse function of an electrical characteristic such as 60 the current consumption in an electrical installation, while the other contact member is adapted to move toward the first contact member at a definite speed upon the occurrence of a predetermined overload in the 65 installation. One of the particular features of novelty of our present invention consists in providing means whereby the minimum time in which the two contact members can move into engagement and complete the circuit of the tripping coil is adjustably determined. To this end, we provide an adjustable stop which determines the minimum 70 distance between the initial position of the contact member having a definite movement and the other contact member. In addition we have provided a novel and improved means for actuating the movable contact member at a predetermined definite or uniform speed, and also means for adjusting the time characteristic of the motion of this contact member. The means which we have devised for carrying out the objects of our invention will be best understood by reference to the accompanying drawings. 75

Referring to Fig. 1 of the drawings there is diagrammatically illustrated conductors 4 of an alternating current electrical installation having translating devices 5 and provided with a circuit breaking device 6. 95 A series transformer 7 of the instrument transformer type is operatively related to the installation, and has its secondary winding electrically connected to the stationary current coil 8 of an inclined-coil ammeter of well known design. A plurality of taps 63 are brought out from the coil 8 so that a variable number of turns may be employed as the active ammeter coil, whereby the same current flowing in the coil 8 may be 100 utilized to produce variable effects upon the moving element of the ammeter by adjusting the number of turns actively included in the coil. In series with the secondary winding of the transformer 7 and 105 110

with the ammeter coil 8 is the winding of an instantaneous overload relay 9. It will thus be seen that the secondary winding of the transformer 7, the ammeter coil 8 and the winding of the overload relay 9 carry a current which is proportional to the current consumption in the translating devices 5 of the installation.

The ammeter is provided with the usual 10 laminated magnetic shielding rings 10, and has a movable element comprising a plurality of magnetic vanes 11 secured to a pivoted shaft 12. A damping disk 13 of aluminum, copper or similar conducting metal is secured to the shaft 12 and is arranged to rotate between the poles of permanent magnets 14. The disk 13 and magnets 14 magnetically damp the movement of the moving element of the ammeter in the well understood manner.

The damping disk 13 has secured thereto a vane 15 which is adapted to engage with an adjustable fixed stop 16. The fixed stop 16 is mounted in a slot 17 of a scale member 18 25 and is adapted to be adjustably fixed at any position in the slot by means of a set screw 66. The moving element of the ammeter and the disk 13 are represented in Fig. 1 of the drawings in substantially their initial 30 or zero positions with the vane 15 resting against a fixed pin 60. Whenever energy is being consumed in the translating devices 5, the disk 13 will move in a counter-clockwise direction, as viewed from above, and the vane 15 will move toward the fixed stop 16. The position of the fixed stop 16 thus determines the maximum movement of the disk 13. A control spring 19 of the usual electrical instrument type is operatively related to the shaft 12 and operates to exert the necessary countertorque upon the moving element of the ammeter.

A contact member 20 is secured by means of a post 21 to the disk 13. A flexible conducting strip 22 electrically connects the contact 20 to a terminal member 23. A second contact member 24 is arranged to move in a path coincident with the path of movement of the contact member 20, and is secured to a pivotally mounted disk 25 by means of a post 26. The disk 25 is adapted to be rotated at a definite speed by a mechanism which will be described in detail hereinafter. A flexible conducting strip 27 55 electrically connects the contact 24 to a terminal member 28.

The instantaneous overload relay 9 is adapted to close the circuit of electromagnets 30 upon the occurrence of a predetermined 60 overload in the electrical installation. The electromagnets 30 are provided with pole pieces 31 between which is arranged an armature member 32 secured to a pivoted shaft 33. A control spring 34 has one end secured 65 to a fixed pin 35 and the other end secured

to the shaft 33. A movable contact member 36 is carried by the shaft 33 and is operatively related to a fixed contact member 37.

An L-shaped arm 38 depends from the lower part of the shaft 33 and has secured thereto one end of a control spring 39. The other end of the control spring 39 is secured to a pivoted shaft 40 which carries the disk 25. The disk 25 is of conducting material, such as aluminum, copper, or similar metal, 70 and is arranged to rotate between the poles of permanent magnets 41. The magnets 41 are secured to a non-magnetic shoe 42. An adjusting screw 43 is operatively related to a stationary yoke 44 and engages in a screw-threaded hole in the shoe 42. It will thus be seen that the effective damping radius of the magnets 41 can be adjusted by turning the screw 43. The yoke 44 is provided with a suitable scale 45 so that the effect of a 75 movement of the magnets 41 can be calibrated. It will further be noticed that the periphery of the disk 25 is of spiral configuration whereby the damping produced by the magnets 41 is not constant throughout a 80 revolution of the disk but varies with the position of the disk.

An electromagnet 50 is operatively related to the disk 13 and is arranged in a manner similar to that of the permanent magnets 14. 95 The electromagnet has a winding 51 connected by conductor 52 to the terminal member 23 and by conductor 53 to the tripping coil 54 of the circuit breaking device 6. A conductor 55 connects the terminal member 10 28 to the terminal member of the movable contact member 36. The stationary contact member 37 is connected to one conductor 56 of a direct current installation, while the other conductor 57 of this direct current installation is connected by conductor 58 to the tripping coil 54. It will thus be seen that the tripping coil 54, the electromagnet winding 51, the contacts 20 and 24, and the contacts 36 and 37 are arranged in series 110 with each other and across the direct current conductors 56 and 57. The windings of the electromagnets 30 are also adapted to be connected across the conductors 56 and 57 by means of the instantaneous overload 115 relay 9. An adjustable resistance 59 is included in circuit with the windings of the electromagnets 30.

The remaining features of construction of our novel and improved inverse time limit 120 relay will be best understood by a brief description of the operation thereof. The apparatus is normally inactive with no current flowing in the windings of the electromagnets 30 and 50. A current proportional to 125 that being consumed in the translating devices 5 flows through the secondary winding of the transformer 7, the coil of the instantaneous overload relay 9 and the ammeter coil 8. The disk 13 therefore takes up a po- 130

sition with respect to its zero determining stop 60 which is substantially a measure of the instantaneous current consumption in the translating devices 5. The disk 25 is in its initial position, which is determined by the engagement of a pin 61 with a fixed stop 62. The pin 61 is secured to the shaft 40 and is positioned behind the L-shaped arm 38, as is clearly indicated in the drawings. The instantaneous overload relay is set to respond to a minimum predetermined overload in the electrical installation. Upon the occurrence of any load greater than this predetermined overload, the instantaneous overload relay 9 will close the circuit of the windings of the electromagnets 30. The energization of the electromagnets 30 causes the armature 32 to rotate in a clockwise direction, thereby winding up the spring 34 and bringing the contacts 36 and 37 into engagement. The movement of the armature 32 is transmitted to the L-shaped arm 38 and energizes or winds up the spring 39. The disk 25 begins immediately to respond to the influence of the energized spring 39 and rotates in a clockwise direction. The rotation of the disk is, however, damped or retarded by the permanent magnets 41, so that its speed of rotation in response to the action of the spring 39 is substantially uniform. By means of the spiral configuration given the periphery of the disk 25, the characteristic curve of movement of the disk can be varied. As illustrated in the drawings the damping effect of the magnets 41 upon the disk 25 is light at the beginning of the rotation of the disk but increases as the disk rotates whereby a suitable modification of the shape of the time-current curve of the instrument may be effected.

The contact member 24 rotates with the disk 25 at a definite speed. The contact member 20, being secured to the disk 13, moves from its zero position as determined by the stop 60 in a counter-clockwise direction toward the contact member 24, a distance which is a measure of the rate of current consumption in the translating devices 5. If the overload continues the contact 24 will engage with the contact 20. The engagement of the contacts 20 and 24 completes the circuit of the tripping coil 54 whereupon the circuit breaking device 6 operates to open the circuit of the translating devices 5. The engagement of the contacts 20 and 24 also energizes the electromagnet 50. This electromagnet may be termed a kick-magnet, since its function is to give the disk 13 a slight forward movement to accentuate the engagement of the contacts 20 and 24. When the winding 51 is energized by means of the tripping current, eddy currents are set up in the disk 13. These eddy currents produce the effect of a shaded pole motor which is increased by the flux of the

permanent magnets 14, which, due to its temporary motor effect, gives the disk a quick kick thus forcing the contacts 20 and 24 more firmly together. This contact accentuating device is more fully described and claimed in the copending application of James R. Craighead, filed Sept. 20, 1916, Ser. No. 121,335. A non-inductive shunt 65 is connected across the winding 51 and has the effect of shunting a certain amount of current from the winding 51, thus decreasing the kick action of the electromagnet 50. By suitably proportioning the resistance 65 any desired kick action can be obtained.

In all inverse time limit relays heretofore known to us there has been a certain definite overload for which the time of operation of all the relays in the installation is the same. This condition is illustrated in Fig. 2 of the drawings. This figure represents the time-current curves A, B, and C of three different inverse time limit relays. It will be evident that for a definite overload, represented by D along the current coordinate, each of the relays will have identically the same characteristic time of operation. This is decidedly objectionable since it results in the simultaneous operation of all the relays in the installation upon the occurrence of this particular overload. Obviously, it is desirable that the relays more remote from the central station should operate sooner than those nearer the central station. One of the particular features of our invention is the provision of means whereby this result can be accomplished in the relay to which our invention relates. In accordance with our invention, the adjustable fixed stop 16 is provided which determines the maximum movement of the contact 20. In this manner the minimum time in which the contacts 20 and 24 can engage may be adjustably determined. The characteristic curves of the three relays may thus be altered as indicated by the curves A', B' and C' of Fig. 3. It will be seen from an examination of the characteristic curves A', B' and C' that each of the relays has a different time of operation for any particular overload, and that in the vicinity of the critical overload, upon the occurrence of which all the relays would normally trip out, each curve has a definite but different straight line time characteristic, whereby the minimum time in which the various relays will energize their respective co-operating tripping coils is different for each relay.

The contacts 20 and 24 are necessarily light since both are mounted on the moving elements of meter type construction. The contact 20 is a small platinum sheet while the contact 24 is a small platinum spring with a small straight end which

slides over the contact 20. These two contacts are suitably insulated from the disks by which they are carried. These contacts are intended only to make and not to break the tripping circuit. The tripping circuit is designed to be opened or broken by the relatively heavy contacts 36 and 37. To this end, the spring 34 is considerably heavier than the spring 39. As soon as the circuit breaking device 6 has opened the circuit of the translating devices 5, the electromagnets 30 will be deenergized. The armature 32 immediately responds to the action of the relatively heavy spring 34 and returns almost instantaneously to its initial position. The contacts 36 and 37 are thereby separated, thus opening the tripping circuit. In the return movement of the armature 32, the L-shaped arm 38 engages the pin 61 and returns the disk 25 to its initial position. The spring 34 is so proportioned that it is adapted to rotate the disk 25 against the action of the magnets 41 at a very rapid speed, so that the disk 25 is returned to its initial position with the pin 61 resting against the fixed stop 62 substantially instantaneously. By this arrangement the apparatus is reset in its initial condition substantially instantaneously after the actuation of the circuit breaking device 6. It will be apparent from the foregoing description that the contacts 36 and 37 disengage an instant sooner than the contacts 20 and 24 whereby any spark resulting from the opening of the tripping circuit occurs at the contacts 36 and 37, thereby protecting the delicate contacts 20 and 24.

If the installation is relieved of the overload before the movable contact 24 engages with the current dependent contact 20, the instantaneous overload relay 9 will open the circuit of the electromagnets 30. The relatively heavy spring 34 then operates to immediately return the armature 32, the disk 25, and the contact 24 to their initial positions, and the apparatus is almost instantaneously restored to its initial condition in readiness to respond to another overload. It will also be evident that the apparatus is similarly restored to its initial condition upon the operation of the circuit breaking device 6, wherefore it is substantially automatic in its operation and requires no attention other than the necessary initial adjustments.

It will be seen from the foregoing description that we have devised a novel and improved construction of relay whereby accurate selective action for different overloads is obtained and certainty of the correct order of operation of circuit breaking switches under all conditions is insured. The meter type construction utilized permits of the highest accuracy in the adjustments and operation

of the apparatus. The use of two movable contacts which approach each other to trip the circuit, the position of one contact being dependent on the amount of the overload while the motion of the other contact is definite, results in securing an unusually satisfactory relation between current and time. Certainty of the correct order of operation of the circuit breaking switches is obtained by the adjustable stop 16 which causes the time characteristic of the apparatus to become definite for currents above any desired value.

The relay of our invention is an inverse time limit relay but the time may be made definite for current values above any desired value by means of the maximum current stop 16 on the ammeter element. The general tendency of time-current curves produced by most inverse time limit relays is to be very steep at the beginning, thus being very selective in respect to current, especially for small current values, but for any considerable current values the time becomes so small that selectively both with respect to time and current is lost. Various attempts to improve these characteristics, for example, by means of inductive shunts, have in general succeeded only in lifting the high current end of the curves, which separates the curves for different time settings and thus becomes selective in respect to time, but the curves being made more flat lose almost entirely their selectivity in respect to current except for very small currents. The characteristics of the time-current curves produced by our inverse time limit relay combine to a marked degree these two features,—selectivity with respect to time and selectivity with respect to current. The curves are not so steep at the beginning but have a gradual slope through a wide range of current; selectivity with respect to current is, therefore, distributed through a wide range of current values and at the same time the current for the different time settings keeps well apart, being selective with respect to time.

The characteristics of the time-current curve of our improved relay may be modified in three ways. First, by means of the different taps on the current coil of the ammeter element. As previously mentioned, the ammeter coil 8 has taps 63 brought out at different numbers of turns of the coil. Connections are made to the desired tap by means of a switch arm 64. Since one of the contacts, namely contact 20, for closing the circuit of the tripping coil 54 is attached to the moving element of the ammeter it will be seen that the taps 63 furnish a means for modifying the characteristics of the time-current curve, since the position which the moving element of the ammeter assumes upon a predetermined

current flowing in the active turns of the coil 8 can be adjusted by varying the number of active turns. Secondly, the time characteristic of the time-current curve may be made definite for current values above any fixed point by means of the maximum current stop 16, thus preventing the time from becoming so small as to make the selectivity with respect to time doubtful. 10 The relay is, of course, not selective with respect to current for current values above the setting of the maximum current stop. And thirdly, the time-current curve may be modified by adjusting the characteristic motion of the disk 25 and hence of the contact 24. To this end the damping magnets 41 may be adjusted by means of the screw 43 to increase or decrease their damping effect upon the disk 25, and the disk may further be 15 given any peripheral configuration to produce the desired time motion of the contact 24.

It will of course be understood that the movable contact 20 may be moved in response to any electrical characteristic of an electrical installation, for example, in response to the voltage or wattage of an installation. We have merely illustrated an ammeter in the accompanying drawings 20 by way of example for the purpose of explaining our invention. Thus, the movable contact 20 may be operatively related to the movable element of the wattmeter or voltmeter in exactly the same way that 25 we have shown and described it operatively related to an ammeter.

Numerous modifications in the details of construction and design of our novel and improved inverse time limit relay without departing from the spirit of our invention 30 will be apparent to those skilled in the art. We do not, accordingly, desire to be limited to the specific construction herein illustrated and described by way of example for the 35 purpose of explaining our invention, but we wish to cover by the appended claims all modifications and applications of our invention within its spirit and scope.

What we claim as new and desire to secure by Letters Patent of the United States, 40 is:—

1. An inverse time limit relay comprising an electric circuit, a movable contact having an initial position and included in said circuit, means for moving said contact at a 45 definite speed, a second movable contact included in said circuit and positioned in the path of movement of said first mentioned contact, means whereby said second movable contact will occupy a position whose 50 distance from the initial position of said first mentioned contact is an inverse function of the current consumption in an electrical installation, and a stop member adjustably positioned to limit the path of 55

movement of said second mentioned contact as desired.

2. An inverse time limit relay comprising an electric circuit, a rotatable element having an initial position, a spring adapted 70 when energized to rotate said element, means for damping the rotation of said element, a contact included in said circuit and operatively related to said element, a second contact included in said circuit and positioned in the path of movement of said first mentioned contact, means whereby said second contact will occupy a position whose distance from the initial position of said first mentioned contact is an inverse function 75 of the current consumption in an electrical installation, means for energizing said spring, and means whereby said element is returned to its initial position substantially instantaneously upon the engagement of 80 said contacts.

3. An inverse time limit relay comprising an electric circuit, a rotatable element, a spring adapted when energized to rotate 85 said element, magnetic damping means for retarding the rotation of said element, means for energizing said spring, a contact included in said circuit and operatively related to said element, a second contact included in said circuit and positioned in the 90 path of movement of said first mentioned contact, and means whereby said second contact will occupy a position whose distance from the initial position of said first mentioned contact is an inverse function of the 95 current consumption in an electrical installation.

4. An inverse time limit relay comprising an electric circuit, two coöperating contacts included in said circuit and adapted to move 100 toward each other to complete the circuit, means whereby one of said contacts is adapted to occupy a position dependent upon the current consumption in an electrical installation, means whereby the effect of a predetermined current consumption upon the position of the current dependent contact may be adjusted, means whereby the second contact may be moved toward the current dependent contact at a definite speed, an adjustable fixed stop adapted to limit the movement of the current dependent contact toward the second contact, and means whereby the rate of movement of the second contact may be altered. 110

5. An inverse time limit relay comprising an electric circuit, a rotatable element having an initial position, a spring adapted 115 when energized to rotate said element, an electromagnet having a movable armature operatively connected to said spring, means for damping the rotation of said element, a contact included in said circuit and carried by said element, a second movable contact having a path of movement coincident with 120

- that of said first mentioned contact, means whereby said second contact is adapted to occupy a position whose distance from the initial position of said first mentioned contact is an inverse function of the current consumption in an electrical installation, and an adjustable stop adapted to limit the movement of said second contact toward said first mentioned contact.
10. 6. An inverse time limit relay comprising an electric circuit, a rotatable element, a spring adapted when energized to rotate said element, means for damping the rotation of said element, a pair of coöperating contacts included in said circuit, means for energizing said spring whereupon the spring moves said contacts into circuit closing engagement to close said circuit, a third contact included in said circuit and operatively related to said element, a fourth contact included in said circuit and coöoperating with said last mentioned contact, and means whereby said circuit is opened by the disengagement of said third and fourth contacts.
25. 7. An inverse time limit relay comprising an electric circuit, a rotatable element, a spring adapted when energized to rotate said element, means for damping the rotation of said element, a pair of coöperating contacts included in said circuit, an electromagnet having a movable armature operatively connected to said spring whereby movement of the armature energizes the spring and operates to move said contacts into circuit-closing engagement, a second spring of greater strength than said first mentioned spring operatively related to said armature and adapted to return said armature and said element to their respective initial positions substantially instantaneously upon the deenergizing of said electromagnet, a third contact included in said circuit and operatively related to said element and having an initial position, a fourth contact included in said circuit and coöoperating with said last mentioned contact, means whereby said fourth contact will occupy a position whose distance from the initial position of said third contact is an inverse function of the current consumption in an electrical installation, and an adjustable stop adapted to determine the minimum distance between said fourth contact and the initial position of said third contact.
55. 8. The combination with an electrical installation of an inverse time limit relay comprising two movable members arranged to move toward each other, means for modifying the circuit conditions of said installation upon the engagement of said members, means operative upon the occurrence of any overload in said installation exceeding a certain value for causing said members to move into engagement in a time interval which is an inverse function of the magnitude of the overload when the magnitude of the overload is less than a predetermined value and for causing said members to move into engagement in a constant definite time interval independent of the magnitude of the overload when the magnitude of the overload is greater than said predetermined value, and means for adjusting the magnitude of the overload above which the members will engage in a constant time interval independent of the magnitude of the overload.
9. The combination with an electrical installation of an inverse time limit relay comprising two movable members arranged to move toward each other, means whereby one of said members will occupy a position dependent upon the current consumption in the installation, means for moving the other member toward and into engagement with the current dependent member upon the occurrence of a predetermined electrical condition in said installation, a mechanical stop adjustably positioned to limit as desired the distance which the current dependent member can move toward the other member, and means for modifying the circuit conditions of said installation upon the engagement of said members.
10. The combination with an electrical installation, of a relay comprising two coöperating contacts, means for causing one of said contacts to take up a position which is a measure of the current in the installation, means for moving the other of said contacts in response to an overload in said installation in excess of a predetermined amount at a definite speed into engagement with said positioned contact, and independent adjustable means for varying the extent of movement of said positioned contact.
11. An inverse time limit relay comprising an electric circuit, two coöperating contacts adapted to be moved into engagement to complete said circuit, means for moving one of said contacts over a path to assume a position which is a measure of an overload in an electrical installation, means for moving the other of said contacts into engagement with said positioned contact at a definite speed, and separate adjustable means for preventing the movement of said positioned contact beyond any predetermined point in its path of travel.
12. An inverse time limit relay comprising an electric circuit, two coöperating contacts adapted to be moved into engagement to complete said circuit, means for moving one of said contacts over a path to assume a position which is a measure of an overload in an electrical installation, means for moving the other of said contacts into engagement with said positioned contact at a defi-

nite speed, and an adjustably positioned member coöperating with said positioned contact to limit its path of movement.

13. The combination with an electric circuit of an inverse time limit relay comprising two coöperating contacts movable into engagement, an ammeter element for causing one of said contacts to take up a position which is the measure of the current 10 consumed in said circuit, means for moving the other of said contacts at a definite speed into engagement with said positioned con-

tact, and mechanical means associated with said ammeter element to adjustably determine its extent of movement whereby the 15 position of said positioned contact is varied at will.

In witness whereof we have hereunto set our hands this 14th day of September, 1914.
